UNITED STATES PATENT OFFICE.

CHARLES DE MINICO, OF PORTSMOUTH, OHIO, ASSIGNEE TO UNITED SHOE MACHINERY COMPANY, OF PATERSON, NEW JERSEY, A CORPORATION OF NEW JERSEY.

SHOE-SHAPING MACHINE.

1,085,595.

Specification of Letters Patent.

Patented Feb. 3, 1914.

Application filed May 5, 1910. Serial No. 559,479.

To all whom it may concern:

Be it known that I, CHARLES DE MINICO, a citizen of the United States, residing at Portsmouth, in the county of Scioto and State of Ohio, have invented certain Improvements in Shoe-Shaping Machines, of which the following description, in connection with the accompanying drawings, is a specification, like reference characters on the drawings indicating like parts in the several figures.

This invention relates to machines for use in the manufacture of boots and shoes and particularly to improvements in shoe shaping apparatus.

In the manufacture of shoes the upper materials are stretched over the last as a form and the marginal portions laid down upon the innersole and secured thereto after which the outersole is applied to the shoe bottom. The upper stretching and overlaying mechanisms are constructed and arranged primarily for performing the functions suggested by their names and it is usually necessary to do additional shaping of the shoe on the bottom and side faces adjacent to its edge for forming a suitable seat for the outersole to be laid upon and for giving to the sides of the finished shoe the trim appearance and well defined conformation to the contour of the last which is desirable. It has been customary to perform these last-named functions by beating the shoe with a hand hammer although mechanical beaters have been devised and are now quite extensively used, some of which beat the bottom of the shoe or "pound up" the shoe as it is called in the shoe shops while others both pound up the shoe and beat or "block" the sides of the shoe, and yet others are side beaters only. Whether these operations are performed by hand or by a machine designed for the purpose they have constituted separate operations in the manufacture of a shoe and required one or more additional handlings of the shoe. In the development of shoe making in recent years perfection has been sought by dividing processes and adapting machines and methods and training operators to do one step in the best and most expeditious way. In this manner excellence of product has been obtained from the lasting and the pounding up and blocking operations.

It is an object of this invention to combine in one machine the several instrumentalities required for the shoe shaping operations, thus producing a combined machine including lasting means and pounding up, or blocking, or both pounding up and blocking means, in the use of which a single handling of the shoe will be required and the subordinate operations will be performed without increasing materially, if at all, the time usually required for the lasting operations alone.

The invention is shown, by way of example, as embodied in a special form of lasting machine of the hand method type shown in United States Letters Patent No. 584,744. In order to obtain the above stated object in a relatively complicated and highly organized machine like this a very careful co-ordination of the several instrumentalities is required to obtain a combined action which will possess the effectiveness of the separate operations.

A very important feature of this invention consists in the combination with means for working a portion of an upper over a last, including means for rubbing the upper hard down upon the last bottom, of means for beating the upper.

It is also new by this invention to provide means to rub an upper over a last, then uncover the upper to allow it to react and then to beat the upper to flatten it down upon the last bottom for forming a seat for the outer sole.

A new feature of this invention is found in the combination with the upper overworking means, and means for tacking or otherwise fastening the upper, of means for subsequently beating the overworked and fastened portion of upper to flatten it down for a seat for the outersole, as well as in the combination of automatic devices operating successively in the same cycle of the machine to tack the upper and after the tack has been driven to beat the portion of the upper that has been tacked. It is well understood that after a portion of upper has been overworked and a tack driven to secure it and the overworking means has been withdrawn the upper rises and pulls back or reacts more or less in adjusting itself to its new position and to the lines of strain maintained by the tack. By allowing this reaction to occur

first the beating operation flattens the upper down in the position which it will eventually occupy and forms a smoother seat for the outersole than would be obtained by beating the upper before the reaction takes place.

As herein shown the overworking means is embodied in a horizontally reciprocating wiper, through which operates the tack driver, and the beater is a substantially vertically reciprocating pounder which rises from the work and remains above the wiper while the latter rubs the upper inwardly from the edge of the shoe bottom and holds it while the tack is being inserted. Then, after the wiper has been retracted to uncover the upper the pounder is driven downwardly against the shoe bottom upon the portion of upper which has just been overworked.

It is also a new feature of this invention to provide means to insert a tack and means for thereafter pounding the stock which has been secured by the tack, as distinguished from driving a tack and simultaneously pounding the stock by the tack guide or holder.

Preferably the machine will be organized to cause the bottom beating means to deliver a plurality of blows upon each overworked portion of upper. As herein shown this is done by giving two reciprocations to the beater for each reciprocation of the wiper. In accordance with a further feature of this invention provision is made for giving to the blows on the same portion of stock different qualities. In the illustrated embodiment of the invention the shoe is mounted upon a jack or a heel spindle, this particular machine having been fitted up for heel seat lasting only, which is connected to the driving mechanism of the machine to change the vertical position of the shoe between successive beating blows, the shoe being lifted to receive the second blow. This jack, which in itself is not a part of the present invention, also coöperates with the lasting means to obtain superior lasting, particularly of the heel seat of the shoe. For this purpose the lifting of the jack is timed to take place with relation to the movement of the wiper so that the shoe is raised during the advance of the wiper thereover. This movement of the jack to grip the upper against the advancing wiper increases the friction of the wiper on the upper as its proceeds inwardly from the edge of the upper. This enables a stiff portion of upper material like the marginal portion of a heel stiffener to be bent over the edge of the last less abruptly than would necessarily be done if the shoe were fully raised when the wiper started forward. By raising the jack during the advance of the wiper the overbent upper material is drawn inwardly as it is pressed down so that it is drawn in over

the edge of the last instead of being crushed down and bulged outwardly at the side as might occur if the lifting of the jack followed the inward movement.

A further important feature of this invention consists in the combination with lasting and pounding up means which may be arranged in any appropriate way in this combination, of means for beating the side of the shoe. Means is provided for imparting to the side beater a plurality of reciprocations at a period suitably selected with relation to the operation of the lasting and tacking instrumentalities to be most effective upon the intermittently advanced shoe. The blows of the bottom beater are relatively heavy flattening blows while the blows of the side beater are light taps corresponding to those given by a hand operator to shape the upper materials against the side of the last. A bottom rest mounted to roll over the shoe in the direction of feed has a narrow edge to assist in resisting lateral displacement of the shoe by the side beater.

In accordance with another feature of this invention successive blows of the side beater are delivered against portions of the upper which are different distances from the edge of the shoe bottom. As shown this result is obtained by the relative timing of the side beater and the jack lifter whereby the beater strikes the shoe before it is raised to its highest position and again after it has been so raised with relation to the side beater. Preferably the beater strikes a sharp blow, as distinguished from a push or an increased pressure as has heretofore been proposed, just as the wiper is completing its advance, and the action of the beater, wiper and rising jack serves to shape and produce a well defined angular edge on the upper at the junction of the side and bottom faces of the shoe. It may be well here to state that the wiper, as well as the bottom beater and the side beater, is a shaping means within the meaning to be given to that term in this specification.

These and other features of this invention, including certain details of construction and more important combinations of parts will be explained in the following description and then pointed out in the claims.

Figure 1 is a side elevation of a machine embodying the present invention. Fig. 2 is a perspective view showing certain of the operating mechanisms. Fig. 3 is a sectional detail.

The body portion of the machine may correspond in general with the disclosure in said prior patent, the head 2 carrying a cam shaft having a pulley 3 belted to a loose pulley in the base of the machine which may be connected, by operation of a clutch lever 5, with a continuously running

pulley 6. The cam shaft carries a cam 88 connected by a lever 87 with a tack block supporting slide 84. Tacks are supplied by suitable mechanism to the tack block 20 while the latter is in its retracted position. In advancing to position for the tack to be inserted by the driver 90 the block wipes over the shoe bottom, bending the upper materials over the last edge and wiping and laying them down into fasted position upon the innersole to which they are secured by the tack. Grippers may be employed as shown in said patent, to assist the combined wiper and tack carrier 20 in performing the lasting or they may be omitted as in the illustrated machine which is equipped for heel seat lasting. The shoe is pressed upwardly against a bottom rest 12 which is mounted in a bracket attached to the machine frame and carries a freely rotatable disk 14. The disk has a narrow edge which sinks into the shoe innersole when the shoe is forcefully pressed upwardly against it. This enables the rest to resist the lateral push of the wiper and the blows of the side beater. The shoe is supported and intermittently lifted by the jack comprising the heel spindle 22 movably sustained on the forward arm of a lever 24 fulcrumed on the post of the machine. The jack is normally depressed by a spring 25 acting on the rear arm of said lever which arm is connected by a rod 26, yoke 27 and spring pressed plunger 28 with a cam 30 located on the main cam shaft of the machine back of the cam 88 which operates the wiper and tack block and independent of said cam 88. The disk 14 by reason of its thin shoe engaging edge, is adapted to sink into the shoe innersole when the shoe is uplifted thereagainst while the wiper 20 is retracted, thus allowing the shoe to be raised higher at such times than when the wiper forms the height limiting abutment. In the latter case the spring of the plunger 28 takes up the excess movement of the cam 30. That spring also compensates for differences in thickness of the work on the heel spindle.

The bottom beater 40 is on a plunger 42 shown as operating in a substantially vertical bearing in the bracket which carries the bottom rest, although the plunger may be arranged at any desired inclination to the plane of the shoe bottom. The upper end of the plunger 42 has a suitable loose connection with the front end of lever 44 which is pivoted at 43, Fig. 2, and has its rear end operatively connected with a side cam on a cam block 45. The rear end of the lever 44 is sufficiently below its fulcrum 43 so that pressure of the cam longitudinally against the lever tends to swing it about 43 as an axis and to raise the forward end with the plunger 42. The side cam is here shown as having two drops 46 to impart

two blows to the beater during each cycle of the machine, while the wiper cam 88 gives to the wiper one reciprocation for each cycle. The lever is impelled downwardly to give the beating blow by a strong spring 48 and the length of the stroke is limited by an adjustable collar 49 on the plunger so that the bottom beater cannot descend far enough to strike the side beater when no work is in the machine.

The side beater 50 reciprocates in a bracket 52 and has, as herein shown, a contact plate 54 that is pivoted near its lower end for an inward and slightly upward movement of its upper end, against the action of a spring 55, when the plate engages the work. Said plate has a formed face to correspond with the contour of the last and the described movement causes it to tend to press the upper upwardly toward the edge of the shoe as it strikes the work. The side beater is operated by a stud 56 through a spring 58 which encircles the plunger 60 and is adjusted by a thimble 62 carried by an arm of a lever 65. The upper arm of this lever has a roll in a groove 66 in the cam block 45. The groove is shown as having an undulating contour which gives to the side beater six or eight short strokes in each cycle, thus effecting a light rapid tapping on the side of the shoe as compared with the heavier flattening blows of the bottom beater.

The jack cam will preferably be timed to cause it to lift the shoe during the advance of the wiper over the upper so as to produce on the upper a combined overbending and then an inward rubbing and downward crushing action. This cam will hold the shoe up only while the tack is being driven and then relieve the pressure and permit the jack spring to lower the shoe to avoid drag of the wiper thereover in the retreat of the wiper. The bottom beater cam is timed to strike a blow after the wiper has retreated to uncover the stock and while the shoe has been released from hard upward pressure, and said beater cam and the jack cam are timed to cause another blow to be struck and the shoe to be raised to meet the second blow. In the second rise of the jack the wiper is out of the way so that the shoe is pressed up against the thin edge of the bottom rest which sinks into the innersole and allows the shoe to rise higher so that, in effect, the second blow of the bottom beater on the shoe is harder than the first blow. The side beater cam is formed relatively to the wiper cam to cause said beater to strike before the shoe has been fully raised and again while the shoe is pressed hard up against the wiper and this action of the side beater and the wiper serve to set the upper materials in an angular formation at the edge of the shoe. The vertical movement of

the shoe between the blows of the side beater causes those blows to be delivered successively at different distances from the edge of the shoe.

5. The full operation of the machine will be obvious without further explanation.

Having explained the nature of this invention and fully described a preferred embodiment thereof, I claim as new and desire 10 to secure by Letters Patent of the United States—

1. A machine of the class described having, in combination, shoe shaping means including means for upholding the shoe and 15 separate upper rubbing and upper beating devices operating successively during one cycle of the machine on the same portion of the work to engage and rub the upper hard down upon the shoe bottom and then to 20 engage and beat the rubbed down portion of upper.

2. A machine of the class described having, in combination, shoe shaping means including mechanisms for rubbing the upper down upon the last bottom, withdrawing the 25 rubbing means, and then beating the portion of the upper from which the wiper has been withdrawn, all in one cycle of the machine.

30. 3. A machine of the class described having, in combination, means for wiping the upper into lasted position, means for tacking the upper, and means for beating the upper after the rubbing means and the 35 tacker have been withdrawn from the upper, said means all operating on the same portion of the stock during the same cycle.

4. An organized machine of the class described having, in combination; automatically operating devices for working an upper over a last bottom and inserting a tack to restrain displacement of the overworked upper; and means operating upon the same portion of stock during the same cycle, after 45 the overworking means has been withdrawn and the upper permitted to re-act from the tension thereof, to beat the upper for flattening it down upon the last bottom to form a seat for the outer sole.

50. 5. A machine of the class described having, in combination, devices adapted to press a portion of upper over a last bottom into position to be secured to an innersole and to secure the upper, and means operating automatically upon the same portion of stock during the same cycle after said devices have withdrawn from the upper to beat the overworked and fastened portion of upper.

60. 6. A machine of the class described having, in combination, automatic devices operating successively during the same cycle to tack an upper to an innersole and after the tack has been driven to beat the same portion of the upper.

7. A machine of the class described having, in combination, automatic devices movable into the same position one after the other in the same cycle to tack an upper and subsequently to beat the same portion of the 70 upper.

8. A machine of the class described having, in combination, a tacker movable horizontally over the shoe bottom into position to fasten an upper and then withdrawing 75 from such position, and a beater movable vertically to beat the shoe after the tacker is withdrawn.

9. A machine of the class described having, in combination, shoe shaping mechanism including a shaping device movable over the upper in the plane of the shoe bottom, and an independent shaping device movable perpendicularly to said plane for 80 acting upon the same portion of upper.

10. A machine of the class described, having in combination, independent upper shaping devices engaging the outer face of the upper only and operating successively during the same cycle of the machine upon 90 the same portion of the shoe bottom in directions substantially perpendicular to one another.

11. A machine of the class described, having in combination, a wiper and a beater for 95 shaping the upper on the bottom of a shoe, means for operating said wiper and said beater, and means for changing the position of the shoe with relation to the plane of the wiper between the operations of said devices. 100

12. A machine of the class described having, in combination, shoe positioning means and an intermittently operating bottom beater arranged to strike a plurality of 105 blows on the same portion of the work, and means for changing automatically the effective force of successive blows.

13. A machine of the class described having, in combination, shoe positioning means and an intermittently operating bottom beater arranged to strike a plurality of 110 blows on the same portion of the work, said machine having provision for automatically imparting different qualities to alternate blows of the beater.

115. 14. A machine of the class described having, in combination, a wiper, means to reciprocate the wiper over the shoe bottom for shaping the upper thereon, a support for the shoe, means acting therethrough to depress the shoe, and means operating in timed relation to the wiping movement for raising the shoe during the advance of the wiper thereover.

120. 15. A machine of the class described having, in combination, a wiper, means for reciprocating it over the shoe bottom, a support for the shoe, means for raising the support during the advance of the wiper and for relieving the upward pressure of the 125 130

- shoe against the wiper prior to the retraction of the wiper.
16. A machine of the class described having, in combination, a shoe bottom beater, 5 means for actuating said beater, a shoe support, and means for uplifting the shoe support to meet each alternate blow of the beater.
17. A machine of the class described having, in combination, a wiper; a tacker; a beater; a shoe support; actuating mechanism for said parts including means for raising the shoe support to resist the action of the tacker, releasing said shoe support during 15 the retraction of the wiper, causing the beater to deliver a blow, and then raising the support to present the shoe for a second blow from the beater.
18. A machine of the class described, having in combination, wiping means, pounding-up means, and blocking means each independent of the others and independently actuated and all operating in timed relation for shaping the shoe, substantially as 25 described.
19. A machine of the class described having, in combination, a wiper, a side beater, and operating mechanism for said devices arranged to cause the beater to strike a plurality of blows against the side of the shoe for each actuation of the wiper.
20. A machine of the class described having, in combination, a horizontally reciprocating wiper, a tack driver operating 35 through the wiper, and a beater arranged to reciprocate perpendicularly to the movement of the wiper and arranged to rise from the work and remain above the wiper while the latter rubs the upper inwardly from the 40 edge of the shoe bottom and holds it for the insertion of the tack by the driver.
21. A machine of the class described having, in combination, a wiper, a beater, a shoe support, means for actuating the shoe support 45 to raise the shoe during the advance of the wiper, and means for actuating the beater to strike a plurality of blows against the side of the shoe which are timed to take effect at different distances below the edge 50 of the shoe.
22. A machine of the class described having, in combination, a wiper, a shoe support, means for actuating the shoe support to raise the shoe during the advance of the 55 wiper, and means for actuating the beater to strike a plurality of blows during the movement of the wiper which are timed with relation to the shoe support movement to take effect at different distances below the 60 edge of the shoe.
23. A machine of the class described having, in combination, a wiper, a shoe support, means for relatively actuating the wiper and shoe support in predetermined time 65 relation to compress the stock between the wiper and the last bottom, and means for heating the side of the shoe while the stock is so held under compression.
24. A machine of the class described having, in combination, a horizontally reciprocating wiper, a tack driver operating 70 through the wiper, a beater arranged to reciprocate perpendicularly to the movement of the wiper and to rise from the work and remain above the wiper while the latter rubs the upper inwardly from the edge of the shoe bottom and holds it for the insertion of the tack by the driver, and means thereafter to drive the beater downwardly against the shoe bottom upon the portion of upper which has just been overworked by the wiper and fastened by the tacker. 75
25. A machine of the class described having, in combination, lasting means, a beater for acting upon the side of a shoe adjacent to the edge of the shoe bottom, means for actuating said beater, a shoe support, and means for uplifting the shoe support in time relation to the movements of the lasting means and beater and operating automatically to position the shoe at different altitudes for successive blows of the beater. 80
26. A machine of the class described, having in combination, a wiper movable inwardly across the edge of the shoe bottom 95 and retreating from over the shoe bottom, a bottom rest to determine the vertical position of the shoe when the wiper is retracted and to guide the shoe in its feeding movements for presenting different portions of the shoe edge to the operation of the wiper, said bottom rest comprising a freely rotatable disk turning about an axis parallel with the direction of the wiper movement and having a thin shoe-engaging edge, 100 extending at right angles to the direction of the wiper movement, substantially as and for the purpose described. 105
27. A machine of the class described having, in combination, a wiper movable from 110 and toward shoe-engaging position, a beater arranged to strike the shoe bottom while the wiper is in shoe-engaging position and also when the wiper is out of shoe-engaging position, a shoe bottom rest having a thin shoe-engaging edge, a shoe support, means to actuate said support to press the shoe against the wiper and said rest and also thereafter to press the shoe upwardly to meet the blow of the beater when the wiper is retracted, the thin edge of said rest permitting the disk to sink into the shoe innersole and allow the shoe to be raised higher for receiving the second blow of the beater than the wiper permits it to be raised for 115 receiving the first blow of the beater. 120
28. A machine of the class described, having in combination, two automatically operated separately mounted tools adapted to shape the upper one by impact and the 125

- 6
- other by rubbing pressure, said tools being arranged to act successively on the same portion of stock in direction substantially perpendicular to one another.
- 5 29. A machine of the class described having, in combination, devices operating intermittently to press and fasten a portion of upper in lasted position, and means operating automatically to beat the same portion of the upper after said devices have left contact with the fastened portion of the upper and during the same cycle of the machine in which the fastening operation is performed.
- 10 30. A machine of the class described having, in combination, means operating automatically for performing a plurality of operations upon a shoe in succession during a single cycle of the machine, a shoe support, power driven means for actuating it to lift the shoe, a plurality of devices formed to resist the lifting movement of the shoe to different degrees, and means for withdrawing from operative position during a portion of the cycle, while the lifting means is acting, the device offering the greater resistance whereby the support is permitted to lift the shoe into different positions to receive successive actions of the 25 first mentioned operating means.
- 30 31. A machine of the class described hav-
- ing, in combination, a side beater, mechanism to present the shoe for the action of the beater upon the shoe and means to change automatically the vertical relation 35 of the shoe and the side beater during the machine's cycle to cause the beating to take place at different distances from the edge of the shoe bottom.
32. A machine of the class described having, in combination, a side beater, mechanism operating automatically to present the shoe during the same cycle of the machine successively in different planes for the 40 action of the beater upon the shoe at different distances from the edge of the shoe bottom.
33. In a machine of the class described, the combination with automatic means operating to elevate and hold a shoe alternately at different heights in the same cycle 45 of the machine, of a side beater acting on the side of the shoe a plurality of times in each position of elevation.
- In testimony whereof I have signed my 50 name to this specification in the presence of two subscribing witnesses.

CHARLES DE MINICO.
